CHARLES M. TEMPLETON, OF CONCORD, NEW HAMPSHIRE.

Letters Patent No. 71,664, dated December 3, 1867.

IMPROVEMENT IN STUFFING-BOX PACKING.

The Schedule referred to in these Letters Patent and making part of the same.

TO ALL WHOM IT MAY CONCERN:

Be it known that I, CHARLES M. TEMPLETON, of Concord, in the county of Merrimack, and State of New Hampshire, have invented a new and useful Improvement in Packing-Boxes and Metallic-Steam Packing for Steam-Engines; and I do hereby declare that the following is a full and exact description thereof, reference being had to the accompanying drawings, and the letters of reference marked thereon, of which drawings—

Figure 1 is a lateral section of my packing-box and packing-rings in position when in use except when the piston-rod or stem is removed.

Figure 2 is a section of the same with the follower and packing-ring removed, and also without the piston-rod or valve-stem.

Figure 3 is a side elevation of the inner portion of my packing-ring.

Figure 4 is a plan of the top of the inner portion of my packing-ring.

Figure 5 is a section of my packing-ring and follower, with the piston-rod or valve-stem in place.

Figure 6 is a section of my follower without the packing-ring, and with the rod or stem removed.

Figure 7 is a section of the packing-ring.

Figure 8 is a plan looking down into the follower.

Figure 9 is a plan of the top of my packing-ring.

Figure 10 is an isometrical drawing of one-half the follower, showing the inside thereof, and the bevels on the inside thereof.

Figure 11 is an isometrical drawing of my packing-ring, with one section or segment thereof removed to show the inside thereof, and the arrangement of the parts.

Figure 12 is an isometrical drawing of the section or segment of my packing-ring which completes fig. 11.

Figure 13 is a plan of the bottom or lower end of my packing-box, of which fig. 1 is a section, and shows the position of the apertures pierced through said box for the admission of steam to act upon the bottom of the follower.

The nature of my invention consists in constructing a metallic packing capable of expansion and contraction, in such manner as to clasp the piston-rod or valve-stem tightly when working steam, and partially releasing the same when steam-pressure is relieved, and in adapting the packing-box to the purposes of my invention.

To enable others skilled in the art to make and use my invention, I will proceed to describe its construction and mode of operation.

I construct my packing-box of any required size, substantially in the form indicated by the portions of figs. 1 and 2, marked P. I place at the bottom of said packing-box, the composition lining or bushing L, which is fixed in its place, and through which passes the rod or stem, and above this lining or bushing, and in a groove turned for the reception thereof, I place a spiral spring, the use of which will be hereinafter more fully explained. I then construct my follower F, (fig. 6,) which fits in the inside of my packing-box in the chamber marked D, in fig. 2. My said follower is constructed in the shape indicated in the drawing, fig. 10, and bevelled inside, as shown in said fig. 10, and in the sections, figs. 1, 5, and 6, and inside thereof is placed my packing-ring, which is operated by said follower as hereafter shown. And said follower, when in place, rests on the said spiral spring, and a small steam-chamber is left between said follower and the lining or bushing L, and said steam-chamber is connected with the cylinder or steam-chest by the apertures h h h, (fig. 13.) I then construct my packing-ring in three sections or segments, and each section or segment is composed of two parts, the outer portion marked R, and the inner portion marked r, (fig. 12,) and said parts are further shown in the sections, figs. 1, 5, and 7. Said packing-ring is shaped to the piston-rod or valve-stem, and the ends of the segments thereof filed away, to permit said ring to close round said rod or stem, as said follower acts upon said ring, or as said ring, or piston-rod, or stem is worn away by friction. And when the portions composing said ring are in place, they are in position shown by the plan of the top of said ring, (fig. 9,) and in the drawing, fig. 11. The said outer and inner portions are arranged to break joints, as shown in said figures, and are kept in their relative positions by small steady-pins, inserted for the purpose of preventing said outer and inner portions from revolving upon each other, so that the joints may fall together and thus permit the escape of steam. The letters A A, B B, C C, a a, b b, c c, are stamped upon the outer and inner segments of my packing-ring, simply as guides in adjusting the same in place. To close the top of my packing-box, I construct the gland T T, (figs. 1 and 2,) with the bushing or

lining L' L', through which passes the piston-rod or valve-stem. The face of said gland fits into the groove around the edge of said packing-box, as shown in figs. 1 and 2, and the said packing-ring is ground, so that the top thereof fits to the face of the said gland accurately and steam-tight, and said gland is held in its place by screws as the glands of ordinary packing-boxes are held in place. The position of said screws is indicated by the dotted lines in said figs. 1 and 2. To adjust my packing in position for use, I place said packing upon the rod or valve-stem, as shown, fig. 5, and it is then placed in the chamber D, (fig. 2,) and the gland screwed in place, and the packing will then be in the position indicated in the section, fig. 1; the piston-rod or valve-stem passing through the groove or aperture therefor, shown in said section. The spiral spring coiled around the chamber C, (fig. 1,) acts only to hold the follower and packing-ring up to the face of the gland with sufficient force to prevent the same from rattling when steam is not acting upon the bottom of said follower, and also to prevent sediment from collecting between said face of said gland and the face of said ring, as would be unavoidable in case said ring should be allowed to drop away from said gland when steam was not applied. It will be understood that when in use the lower or bottom end, (speaking with reference to the drawing, fig. 1,) is attached to the cylinder-head or steam-chest.

To explain the operation of my packing, I will suppose the steam to be admitted to the cylinder upon the side of the piston-head next the packing-box. The piston-rod will by the movement of the piston be drawn into the cylinder, and the expansive force of the steam, admitted to the small chamber C through the apertures h h, will exert upon the bottom of the follower the same pressure per square inch that it exerts upon the piston-head itself. This pressure upon the bottom of the follower, forcing the same upwards or outwards, will obviously cause the bevels upon the inside thereof to act with a corresponding degree of force upon the bevels on the outer periphery of my packing-ring, and the external and internal bevels of my follower being at the same angle with the piston-rod, the said packing-ring will close together upon the rod equally at the bottom and top of my ring, and at the same time, by the same pressure, the outer face of said packing-ring will be forced against the face of the gland T T, thus forming simultaneously two steam-tight joints, one of said joints being formed around the rod or stem by the inner surface of my packing-ring, and one formed upon the gland by the face of said ring. It will be observed that the steam which may penetrate along the piston-rod, through the bottom of my follower to my packing-ring, cannot escape farther. Not through the ring itself, for the segments of the outer and inner portion thereof, break joints, and the outer periphery of the inside ring r r is accurately fitted to the outside ring, the parts thereof being subjected to no friction or attrition to impair the accuracy of the joints between the two. Nor can steam escape along between the rod or ring, for the reason that said ring is compressed upon said rod in a steam-tight joint by the action of the follower. Nor can it escape along between the inner periphery of the follower and the outer periphery of the ring, because it will be arrested by the gland fitting in the groove around the packing-box. Nor between said gland and the face of the packing-ring, because of the joints of the packing-ring upon the gland made simultaneously with the joint of the ring upon the rod or stem by the action of the follower. The piston-rod having passed into the cylinder to the full length of the stroke, the steam enters the other side of the piston-head and forces out the rod. The steam exhausts in outer end of the cylinder, and the pressure upon the bottom of my follower is relieved, and the clasp of the packing-ring upon the rod is freed by reason thereof, and the friction of the packing upon the rod is correspondingly lessened. In case my packing is applied to valve-stems, in this case the pressure of the steam, when steam is given the engine, is not unequal as when applied alternately to one and the other side of the piston-head. But said pressure acts constantly upon the steam-chest and upon the bottom of my follower, and with a corresponding constancy upon my follower, without regard to the direction in which the valve-stem is moving, and of course the clasp of the packing on the valve-stem is constant and equal. There must of course be a constant attrition between the packing and the rod or stem working through the same, and the rod or stem and packing are constantly wearing away. As my packing wears away upon its inner surface, it will be seen that my follower, travelling outward on the bevels of the ring, will hold said ring to the rod in the same relative position as when first adjusted, and my packing must last until the inner segments r r r of said packing-ring are nearly worn away by friction.

My follower and packing-rings are made of brass or composition metal, and may be made of any metal adapted to the purpose, and will long outlast any fibrous material that is in use for packing.

What I claim as my invention, and desire to secure by Letters Patent, is—

The packing-ring, consisting of the outer parts R R R, and the inner parts r r r, the same being arranged to break joints with each other, in common with the follower F, all operating as and for the purpose described.

CHARLES M. TEMPLETON.
